UNITED STATES PATENT OFFICE.

EDMOND KELLEY, OF BOSTON, MASSACHUSETTS.

HYDROPOWER-BEATER.

1,327,395.

Specification of Letters Patent.

Patented Jan. 6, 1920.

Application filed August 19, 1918. Serial No. 250,492.

To all whom it may concern:

Be it known that I, EDMOND KELLEY, a citizen of the United States, residing at Boston, in the county of Suffolk and State 5 of Massachusetts, have invented new and useful Improvements in Hydropower-Beaters, of which the following is a specification.

The present invention relates to machines adapted to stir, whip, or beat liquid and 10 semi-liquid fluids and compositions for such purposes as to produce a froth, thoroughly mix a number of ingredients or separate butter fat from cream and so forth; and its principal object is to furnish an improved 15 machine of this type, which is driven by water power and by which the energy in the water is converted into work more efficiently and with smaller expenditure of water than other devices of similar type 20 heretofore suggested. Further objects are to provide such machine with provisions by which the machine may be mounted upon and supported by the water tap or faucet of a domestic plumbing system, and with 25 means by which the waste water from the motor may be discharged against the outside of the jar or container in which the liquid is confined and on which the motor is mounted.

30 The invention consists in the machine hereinafter described in detail in the following specification, and in all equivalents thereof and the principles underlying the same as pointed out in the appended claims.

35 In the drawings, Figure 1 is an elevation of a machine embodying my invention in the form which at present I prefer to others. Fig. 2 is a plan view of the machine shown in Fig. 1, but represented with the outer 40 casing or guard removed. Fig. 3 is in part an elevation and in part a vertical section, on a larger scale than Fig. 1, of the motor of the machine and the connections and conduits by which a supply of water is directed 45 thereto. Fig. 4 is a cross section on line 4-4 of Fig. 3.

The same reference characters indicate the same parts in all the figures.

In the drawings 11 represents a jar or 50 container, which is preferably of glass and which may be of any desired size and shape. That here shown is a cylindrical jar of about one quart capacity. 12 is the cover of the jar, which is here shown as a screw cap 55 of familiar type adapted to be engaged with threads formed on the jar surrounding its

mouth. Instead of this specific cover, however, one of any other desired form applied and secured in any other desired way may be used. 13 represents a dasher or beater 60 which is contained within the jar 11 and is adapted to stir and agitate the contents of the jar. The specific beater here shown is made of a number of wires having such length and being so bent as to produce the 65 desired effect, and secured to a shaft 14. Any other specific form of beater or dasher suitable for any other particular use to which the machine is intended to be put, may be used in place of the one shown. 70

Preferably the dasher is adjustable so as to act in different vertical zones of the jar, and to make it so its shaft may be telescopic, consisting of a sleeve to which the numeral 14 is applied, and a driving shaft 15 which enters such sleeve, and on which the latter is adapted to slide endwise. Any other form of adjustable and contractible shaft, or any other means for adjusting the dasher may be used, however, without departing 80 from the invention.

Said cover 12 is the supporting base for the motor now about to be described and upon it there are mounted two tubes 16, or as they may otherwise be described, posts 85 having interior passageways, which are widely separated at their lower ends where they are secured to the cover, and are brought together at their upper ends, making an A-shaped frame. There may be more than two of these tubes or posts, if desired, or only one; but I prefer two, for various reasons. Their upper ends are connected to, and their passageways open into, a connection 17 which is externally threaded downward from its upper end and has an outstanding flange or ledge 18 below its threaded part. The fitting 17 may for the purpose of this description be called a nipple. 90

On the central part of the cover or base 100 12, between the posts 16 is a raised pedestal 19 which has a recess 20 in its upper face adapted to contain a series of balls 21, and forming thus a race for a ball bearing. Preferably such pedestal is formed out of 105 sheet metal, which may be integral with the cover, the latter being also of sheet metal, or it may be of a separate piece suitably attached to the cover, and the ball race is preferably made by forming the sheet metal 110 pedestal as shown in the left hand side of Fig. 3. Other constructions may, however,

be used at will. The bottom of the recess or ball race is provided with a wear plate 22 on which the balls 21 directly bear, said plate being preferably of hardened steel, 5 and therefore having greater power to resist wear by the balls than has sheet metal of the sort adapted to be formed into the pedestal as described. Shaft 15 passes through the center of the pedestal and of the ball race described, and has attached to it a plate 23 and a series of vanes 24. Said plate 23 rests upon the balls 21, and is provided with a flange 25 which extends below the top of the pedestal and guards the ball bearing to prevent entrance of water thereinto. Preferably a hard wear plate or washer 26 is secured to the under side of the plate 23 and engages directly with the balls. 27 designates a spacing ring for the balls which 10 surrounds the shaft, but is not connected thereto, and has a number of equally spaced pockets receiving the balls freely and spacing them at proper distances from one another in the ball race. 15 Preferably the plate 23 and flange 25 are made in one piece out of sheet metal, and the vanes 24 are also made of sheet metal pieces soldered at their inner edges to the shaft and at their lower edges to the plate 20 23. The upper end of the shaft turns in a step bearing 28 fixed between the upper ends of the posts 16. 25 The posts have openings 29 forming nozzles through which jets of water may issue, 30 and being placed to direct such jets against the vanes, in the most efficient direction, and the vanes are preferably curved according to principles familiar in connection with hydraulic turbines, and as indicated in Fig. 40 2, whereby to utilize efficiently the velocity and momentum of the jets. Said nozzles 29 are tangential to lines concentric with the shaft and intermediate the inner and outer edges of the vanes. 45 The vanes and tubular posts, with their nozzles, constitute a hydromotor of which the vanes form the rotor connected to the shaft and supported by a ball bearing. This entire motor is mounted upon the cover 12 and forms substantially a part thereof. Means for detachably connecting the posts 50 16 to the cover are shown in Fig. 3 as consisting of screws 30 passing through the cover into the ends of the posts. 55 31 is a guard made preferably of sheet metal formed to surround rather closely the motor and having a lip 32 at its upper end which rests on the flange 18, and is secured thereon by a coupling 33 and an interposed 60 packing washer 34. Said coupling is screwed upon the nipple 17 and extends above the same, being internally threaded so that it may be screwed upon a threaded faucet. It is provided with an internal shoulder 65 35 for supporting a washer 36 to pack

the joint between itself and the faucet. The guard 31 thus described confines the waste water thrown off from the motor and guides it downward. The lower edge of the guard is formed with an inwardly curved or inclined lip 37 which checks the velocity of the escaping water and also directs such water against the jar, so that it flows down the outer surfaces of the jar without spattering, and with the effect of cooling the 70 contents of the jar. This lip is preferably far enough below the cover to insure that water will not be directed against the joint between the cover and the mouth of the jar. 75

It will readily be understood that when 80 the jar containing fluid to be mixed or beaten is attached to the cover 12, and the latter is connected by the coupling 33 with a water faucet, and the faucet is opened, the water then flowing will drive the dasher, and then 85 flow down along the outer surface of the jar. I have found that the ordinary service pressure with which houses are supplied from a central station gives sufficient volume and velocity of water from the nozzles 90 to drive the dasher with sufficient force and speed to beat anything which it may be desired to beat or stir in a device of this sort rapidly and efficiently; and that the amount of water used is very small. The discharge 95 capacity of all the nozzles together is much less than the full capacity of the common faucet or tap, wherefore the amount of water expended in the short time needed to carry out any beating operation is extremely 100 small.

The particular design and construction of the several parts of the machine here shown has been adopted as satisfactory from the point of view of operativeness, compactness, 105 and pleasing appearance. The posts have been shaped to diverge from the nipple on straight lines in order to impede the flow of water through the interior passageways as little as possible, and the vanes have 110 been shaped to conform to the space between these posts; while the outer guard is conformed to the outlines of the posts. Any other form or design of these parts may be made without departing from the essentials 115 of the invention as hereinafter claimed. So also may the rotor be made otherwise than as separate sheet metal vanes shaped and mounted as described and shown.

What I claim and desire to secure by Letters Patent is:

1. A hydromotor attachment for an automatic beating machine comprising a base adapted to be mounted on a jar to cover the mouth thereof, a pedestal mounted on 125 said base and having a ball race in its upper side, a shaft passing through said pedestal and base adapted to enter the jar, balls in said ball race, a plate resting on said balls and connected to said shaft, vanes mounted 130

upon said shaft, and a conduit rising from said base and extending past said vanes longitudinally, having means for connection with a source of water supply, and 5 having an outlet arranged to direct a jet of water against said vanes, whereby to drive the latter rotatably.

2. A motor comprising a base, posts having internal waterways rising from separated points on said base and converging means for conducting water into the waterways of said posts, a rotor having vanes arranged in the space between said posts and supported upon said base, and a shaft 10 passing from said rotor through the base, said posts having outlets arranged to direct jets of water against the vanes of said rotor whereby to drive the same.

3. A motor for a beating machine comprising a support, a rotor mounted on said support and having vanes adapted to be propelled by impingement of water jets, a shaft connected with said rotor, and a conduit connected to said support and extending longitudinally past the outer edges of 25 said vanes and having an outlet arranged to direct water in a jet against the vanes.

4. A motor for an automatic beating apparatus comprising a nipple adapted to be 30 connected to a source of water supply, diverging tubes extending from said nipple and having interior passages opening from the latter, a support attached to the ends of said tubes, and a rotor mounted rotatably upon said support between the tubes and having vanes, the tubes having outlet nozzles arranged to direct jets of water tangentially of the rotor against the faces of said vanes.

40 5. A motor comprising a nipple adapted to be connected to a source of water supply, diverging tubes extending from said nipple and having interior passages opening into the latter, a support attached to the ends 45 of said tubes, a rotor mounted rotatably upon said support between the tubes and having vanes, the tubes having outlet nozzles arranged to direct jets of water tangentially of the rotor against the faces of said vanes, 50 a thrust bearing against which the rotor bears, and a guard carried by the rotor excluding water from said thrust bearing.

6. A motor for an automatic beating machine comprising a base, a thrust bearing on 55 said base, a rotor having vanes mounted to turn upon said thrust bearing, a conduit having an interior passage for water extending past said rotor and having a nozzle arranged to direct a jet against the vanes, 60 a guard carried by the rotor overhanging the thrust bearing and excluding water therefrom, and an outer shield surrounding the rotor and conduit to prevent outward distribution of the water.

65 7. A motor for an automatic beating ma-

chine comprising a base, a thrust bearing on said base, a rotor having vanes mounted to turn upon said thrust bearing, a conduit having an interior passage for water extending past said rotor and having a nozzle 70 arranged to direct a jet against the vanes, a guard carried by the rotor overhanging the thrust bearing and excluding water therefrom, and an outer shield surrounding the rotor and conduit to prevent outward distribution of the water; said base having means for mounting it over the open mouth of a container, and the shield having an inwardly directed lip at its lower edge for conducting the discharged water against the 80 outside of such container.

8. A motor comprising a base having means for making supporting connection thereof with a container, a thrust bearing on said base, a rotor having vanes supported 85 on said thrust bearing, a post rising from the base beside and over the rotor having a step bearing for centering the rotor, said post having an interior water way and an outlet therefrom arranged to discharge 90 water against the vanes of the rotor, and a coupling connected to the post in communication with the water way thereof having means by which it may be secured to a water faucet.

9. A motor comprising a base having a raised pedestal with a depression in the top thereof providing a ball race, balls occupying said race providing a ball thrust bearing, a rotor supported by said bearing and having vanes, and a tube mounted on the base extending therefrom beside said rotor, having means for connection to a water-supplying conduit and having a lateral orifice or nozzle arranged to discharge water 105 against the vanes of the rotor.

10. A motor comprising a base having means for making supporting connection thereof with a container, a thrust bearing on said base, a rotor having vanes supported 110 on said thrust bearing, tubes rising from points on the base at opposite sides of the rotor and converging to a meeting point over the rotor, and means common to the tubes for conducting water thereto; the 115 tubes having lateral outlets arranged to direct water against the vanes of the rotor.

11. A motor for an automatic beating machine comprising a nipple adapted to be secured to a conduit for fluid, diverging passages leading from said nipple, a rotor having vanes mounted rotatably between said passages, there being nozzle openings from the passages arranged to direct impelling jets against the rotor vanes, a thrust bearing supporting said rotor, and structural connecting means uniting said passages and bearing, and having provisions for attachment to a container, and a shaft extending from said rotor and driven thereby.

12. A motor for an automatic beating machine comprising a base part adapted to be mounted upon a container over the mouth thereof, a conducting passageway for fluid, a nipple opening into said passageway, bearings alined beside the passageway, all the aforesaid parts being structurally connected; and a rotor having vanes mounted by said bearings beside the passageway, the latter having a jet orifice arranged to discharge a jet of fluid against the rotor vanes in a direction generally tangential to their path of rotation.

13. A motor for an automatic beating machine, comprising diverging passageways for the motive fluid, a nipple for connection to a conduit, connected with and open-

ing into said passageways, a bearing secured in the angle between said passageways, a base adapted to be mounted on a container over the mouth thereof connected as a part of the same combined structure with the passageways and having a raised pedestal part between the lines of said passageways, the pedestal part forming a thrust bearing, and a combined rotor and shaft structure supported and guided by said bearings and having vanes; the passageways having nozzle outlets arranged to direct impelling jets against said vanes. 20 25 30

In testimony whereof I have affixed my signature.

EDMOND KELLEY.
